UNITED STATES PATENT OFFICE.

HARRY G. ROBBINS, OF MINNEAPOLIS, MINNESOTA.

WALL CONSTRUCTION.

1,106,584.

Specification of Letters Patent. Patented Aug. 11, 1914.

Application filed July 26, 1913. Serial No. 781,340.

To all whom it may concern:

Be it known that I, HARRY G. ROBBINS, citizen of the United States, resident of Minneapolis, Hennepin county, Minnesota, have invented certain new and useful Improvements in Wall Construction, of which the following is a specification.

My invention relates to a fire-proof building wall and the object of the invention is 10 to hermetically seal the horizontal and vertical joints between the blocks composing the wall to the end that the entrance of cold air into the building through the wall will be positively prevented.

15 Other objects of the invention will appear from the following detailed description.

The invention consists generally in various constructions and combinations, all as hereinafter described and particularly pointed 20 out in the claims.

In the accompanying drawings forming part of this specification, Figure 1 is a perspective view of a building wall embodying my invention, Fig. 2 is a horizontal section view of a portion of the wall, Fig. 3 25 is a view of one of the flexible filler plates or pads inserted in the vertical joint between the blocks.

In the drawing, 2 represents the blocks of 30 which the wall is composed. These blocks are provided with a series of openings 3 on each side of the middle portion thereof and a central opening 4, forming, when the blocks are placed in courses in the wall, a 35 series of passages running horizontally through the wall, having the function, as usual in blocks of this kind, of preventing the moisture from passing through the blocks from the outer to the inner surfaces 40 thereof. The longitudinal middle portions of the blocks above and below the openings 4 are also provided with longitudinal recesses 5 extending from end to end of each block and adapted to register with one another when the blocks are placed with abutting 45 ends in the course.

In building a wall, the blocks are laid in courses, one upon another, in mortar 6, and it has been found difficult, if not impossible, 50 to close the joints between the abutting ends of the blocks in the same course and prevent the passage of cold air through the joints and provide a central dead air space in each block that is hermetically sealed at each end. 55 The mortar will drop out of the joints between the blocks, allowing air to enter the

central opening therein and prevent the formation of the dead air space. To avoid this objection, I prefer to omit entirely the use of mortar between abutting blocks in 60 the same course, and provide a filler plate or pad 7 of suitable flexible material, such as felt, or the like, of sufficient width and height to cover the central opening 4 and exclude the entrance of air therein when the blocks are set up in the building wall. The yielding surfaces of these filler plates will conform to the slightly uneven ends of the blocks and when the courses are laid, and the ends of the blocks brought together, the 65 filler plates will be securely held between the blocks in the same course, thereby excluding the passage of air between them and the cracks on each side of the filler plate in the joints will receive the plaster of the inside 70 and outside coats and be concealed thereby when the wall is finished, and as I prefer to provide a filler plate in each vertical joint of the wall, it follows that there will be a central dead air space formed in each block 75 to cut off the passage of moisture through the blocks, while the filler plates will hermetically seal each joint between the abutting ends of the blocks.

To effectually close the horizontal joints 80 against the possible passage of air, I prefer to provide filler strips 8 adapted to fit into the recesses 5 running lengthwise of the blocks and extending for any suitable distance through the course, the filler plates 7 85 being provided with slots 9 therein to receive the edges of these strips at the points where they cross the joints between the abutting ends of the blocks. These strips may be made of felt or any other suitable material 90 that is adapted for this purpose. When these strips have been inserted into the recesses in the blocks, the horizontal joints between the courses will be hermetically sealed and passage of air or moisture 95 through these joints will be entirely prevented. These strips will also hold the filler plates 7 in position between the ends of the abutting blocks. A wall constructed in this manner will have a central dead air space 100 in each block separated at each end by the flexible filler plate from the corresponding air space of the adjacent block. The novelty in this case lies in the use of an insulating filler plate in the joint between the ends 105 of abutting blocks, this insulating plate not only closing the ends of the opening in the 110

block but forming a non-conductor of heat and cold in the joint itself and thereby the entire wall is rendered proof against the passage of air or moisture.

5 I claim as my invention:

1. A wall composed of a series of blocks, each having a narrow central opening extending through the block from end to end thereof and vertically from a point near 10 the top of the block to a point near the bottom thereof, each block having a plurality of longitudinal, independent openings extending from end to end of the block on each side of said central opening, filler 15 plates of insulating material inserted between abutting ends of blocks in the same course and seated against the walls of said central opening and closing and concealing each end of said central openings, whereby 20 a central dead air space is formed in each block separating the longitudinal independent openings on one side of said central opening from the corresponding longitudi-

nal openings on the opposite side thereof, thereby insulating said wall and the joints 25 thereof against the passage of heat and cold.

2. A wall composed of a series of blocks, each having a longitudinal independent opening extending from end to end of the block on each side of a central opening, and 30 filler plates of insulating material inserted between the abutting ends of blocks in the same course and seated against the walls of said central opening and closing and concealing each end of said central opening to 35 form a dead air space separating the longitudinal openings one from the other and insulating said wall and the joints thereof against the passage of heat and cold.

In witness whereof, I have hereunto set 40 my hand this 22d day of July, 1913.

HARRY G. ROBBINS.
